CLOSURE FOR ENVELOPES AND THE LIKE

Albert L. Godoy, Mexico City, Mexico

Application June 21, 1944, Serial No. 541,402

1 Claim. (Cl. 229—79)

This invention relates to closures for envelopes, memoranda books, brief cases, files and other containers.

The object of the invention is to provide a closure the construction of which is such as to permit an envelope or other container to be readily opened or closed without permanently sealing the same, thereby to facilitate inspection of the contents of the container without tearing or otherwise mutilating said container.

A further object of the invention is to provide the closure flap of the container with a sealing tab having a permanently sticky surface coating thereon which coacts with a smooth surface in the body of the container to hold the flap in closed position while, at the same time, permitting the sticky surface of the tab to be disengaged from said smooth surface when it is desired to inspect the contents of the container.

A further object of the invention is to provide the free end of the sealing tab with a terminal lip or finger piece to facilitate the release of the sealing tab without danger of the fingers coming in contact with the adhesive surface of said tab.

A further object is to reinforce and strengthen the closure flap at the point of attachment of the sealing tab thereto, and to print or affix to the body of the container a suitable directive legend visible through said tab.

In the accompanying drawing:

Fig. 1 is a perspective view of an envelope provided with the improved closure and showing the closure flap in open position.

Fig. 2 is a view similar to Fig. 1, showing the flap closed and the tab in sealing position.

Fig. 3 is a vertical sectional view taken on the line 3—3 of Fig. 1.

Fig. 4 is a detail vertical sectional view taken on the line 4—4 of Fig. 1.

Fig. 5 is an enlarged vertical sectional view taken on the line 5—5 of Fig. 2.

Fig. 6 is a vertical sectional view showing the closure in connection with a brief case.

The improved closure forming the subject matter of the present invention may be used in connection with envelopes, memoranda books, brief cases, files and other forms of containers used for holding or transporting letters, documents, papers and the like, and, in Fig. 1 of the drawing, is shown applied to an envelope of standard construction in which 5 designates the body of the envelope and 6 the closure flap thereof, the upper portion of which is provided with a straight longitudinal edge, indicated at 7. Secured to the closure flap 6 and overlapping the upper edge thereof

is a reinforcing strip 8, and secured to said reinforcing strip and to the adjacent portion of the closure flap 6 is a sealing tab 9 having its free end folded transversely upon itself to form a terminal lip or finger piece 10.

That portion of the inner surface of the tab 9 between the finger piece 10 and the reinforcing strip 8, is provided with a permanently sticky surface 11. The adhesive coating 11 on the sealing tab may be of any desired composition which will permit the tab to stick and unstick to facilitate inspection of the contents of the container, and said tab may be formed of paper, Celluloid, or other suitable material with the adhesive applied to the inner surface thereof, or the tab may be constructed of adhesive material known to the trade as "Scotch tape," it being of no great moment as to the particular nature of the material of which the tab is made, so long as the inner face 20 thereof is provided with the aforesaid sticky surface.

Stamped on or fixed to the body of the container in vertical alignment with the sealing tab 9 is a legend 12 preferably consisting of the words "Pull it," which legend is visible through a transparent attaching strip 13 secured to the body of the envelope, as best shown in Fig. 1 of the drawing. The attaching strip 13 is preferably formed of Cellophane or other material having a smooth or glossy exterior surface and which smooth surface coacts with the adhesive material on the sealing tab to hold the closure flap of the envelope in sealing position. Secured to the inner face of the attaching strip 13 at the lower end thereof is a transverse reinforcing strip 14 and this strip 14 is disposed in transverse alignment with the upper edge of the finger piece 10 so that when the sealing tab is in closed position, the finger piece 10 will be opposite the reinforcing strip 14 and thus permit the lip or finger piece 10 to be readily grasped between the fingers and an upward pull exerted thereon to detach the adhesive surface 11 from the attaching strip 13, when it is desired to open the envelope, without liability of the fingers coming in contact with the adhesive material on the sealing tab. The strip 14 also serves to prevent excessive wear on the attaching strip 13, due to the fingers coming in contact therewith during the act of opening the envelope. In order to open the envelope, it is merely necessary to grip the lip or finger piece at the reinforcing strip 14 and exert a slight upward pull thereon, when the sticky surface coating of the sealing tab 9 will become detached 55 from the smooth surface of the attaching mem-

ber 13 and thus permit the closure flap 6 of the envelope to be opened. By closing the flap 6 and pressing the adhesive surface of the tab against the smooth surface of the attaching member, the envelope will be sealed and this operation may be repeated whenever it is desired to inspect the contents of the envelope.

It will thus be seen that there has been provided an extremely simple and inexpensive device by means of which the closure flap of an envelope or other container may be securely held in closed position while, at the same time, permitting ready opening of the envelope and inspection of the contents thereof whenever desired.

As previously stated, the closure may be used in connection with brief cases, memoranda books, and other containers and, in Fig. 6 of the drawing, is shown in connection with a brief case of standard construction, in which 15 indicates the body of the brief case and 16 the closure flap thereof, and to which parts is secured a sealing device the construction and operation of which is similar to that shown in Fig. 1 of the drawing. As many of these sealing devices may be applied to the closure flap of the container as is found desirable or necessary to securely hold the closure flap in closed position and it will be understood that the sealing flap and attaching strip can, if desired, be formed from opaque material instead

of being transparent. It will also be understood that this closure may be used with good results in connection with cigarette packages or the like, when it is desired to obtain access to the cigarettes without tearing or otherwise mutilating the cigarette package. It will, furthermore, be understood that the devices may be made in different sizes and shapes and constructed of any suitable material without departing from the spirit of the invention.

Having thus described the invention, what is claimed is:

A container having a closure flap, an attaching member secured to the container and having a smooth exterior surface, a transverse reinforcing strip on the lower portion of the attaching member, a sealing tab secured to the closure flap and having its free end reverted to form a finger piece adapted to register with said reinforcing strip when the tab is moved to closed position, the inner surface of the sealing tab between the finger piece and adjacent edge of the closure flap being provided with a permanently sticky surface for detachable engagement with the smooth surface of the attaching member and a transversely U-shaped reinforcing strip carried by the free edge of the flap and having one side thereof interposed between said tab and flap.

ALBERT L. GODOY.
